NONSLIP INSERT FOR FLAT SURFACES

Filed Dec. 20, 1923

INVENTOR
George W. Brooks.
BY *Arthur L. Brown*
ATTORNEY

UNITED STATES PATENT OFFICE.

GEORGE W. BROOKS, OF KANSAS CITY, MISSOURI.

NONSILIP INSERT FOR FLAT SURFACES.

Application filed December 20, 1923. Serial No. 681,882.

To all whom it may concern:

Be it known that I, GEORGE W. BROOKS, a citizen of the United States, residing at Kansas City, in the county of Jackson and 5 State of Missouri, have invented certain new and useful Improvements in Nonslip Inserts for Flat Surfaces; and I do declare the following to be a full, clear, and exact description of the invention, such as will 10 enable others skilled in the art to which it appertains to make and use the same, reference being had to the accompanying drawings, and to the figures of reference marked thereon, which form a part of this specification. 15

This invention relates to non-slip inserts for flat surfaces and particularly to friction treads for side walks, steps and the like.

The invention is illustrated as an insert 20 for the treads of concrete steps, the object being two-fold, first to provide a friction non-slip surface which will prevent pedestrians from slipping on the treads when they are moist and to provide wear resisting inserts imbedded in the material of which the 25 steps are constructed and by no means an insignificant feature of the invention is the provision of means for visualizing clear lines of demarkation, denoting the edges of the steps to eliminate liability of mis-stepping 30 on the steps, for example where the steps are made of stone or concrete, it is not always possible to determine the edge of the step or the edge of the platform at the top of a 35 flight of steps, so it is a very easy manner to over-step in descending causing injury which will be eliminated by my invention, so associated with the step tread that a clear line of demarkation will always be present.

40 It is an important feature of my invention that it may be constructed inexpensively of sheet metal and readily inserted in the composition, side walks or steps or other construction, so as to provide an efficient, inexpensive non-slip insert.

In the drawings

Fig. 1 is a perspective view of a step with my invention applied, part of the step being 45 illustrated as broken away to show the construction of the insert.

Fig. 2 is a top plan view of an insert constructed in accordance with my invention.

Fig. 3 is a perspective view of one of the tie members.

Fig. 4 is a fragmentary plan view of a 55 sheet of metal from which the longitudinal bars may be cut.

Fig. 5 is a cross sectional view through the step showing the longitudinal bars of 60 the inserted cross section, and

Fig. 6 is a fragmentary view of a slightly modified form of bar.

In carrying out the invention the sheet 1 of appropriate material is provided and bars or strips 2 are cut therefrom, the edges of 65 which are corrugated or formed of a series of compound connected curves, the bars being cut without loss of material, thus maintaining the cost of production of the insert at a minimum. The bars are preferably 70 punched to provide openings 3 through which concrete may pass so as to hold the insert in its bed. The bars are arranged in parallel longitudinal spaced relation by tie members shown as consisting of V-shaped 75 members 4 having slots 5 therein to receive the bars 2. The triangular members 4 have notched ends 6 and 7 and arranged in pairs so that the free edge of one member will 80 abut against the free ends of the other member of its pair, the two sets of notches 8 forming a central opening to receive a bolt 9 with a nut 10 thereon so that the braces 4 may be fastened to the end side bars 2. The bolts 9 may be stove bolts if desired and 85 these are recommended on account of cheapness.

The braces 4 may be of any preferred material, the longitudinal bars and the braces being preferably arranged diamond 90 shaped as shown, making up an insert which may be imbedded in a surface to provide friction and to increase the wearing quality of the structure in which they are imbedded. For example, after they are imbedded in the 95 step 11, the points 12 of the bars will be practically flush with the surface of the step so that they will be visible and so that the foot of the pedestrian may contact with the edges of the insert bars and obtain a 100 friction grip on the surface to prevent slipping and also to provide against wear, since the wearing qualities of the metal will greatly exceed that of the concrete.

The tie bars are also visible and the frame is so constructed that it will tend to make the width of the step apparent so that the pedestrian will not be liable to mis-step in ascending or descending.

Since the diamond shaped braces will define the width of the step at the base of the riser of the step and the inner edge of the tread, I may provide a wear plate or rail 13 having inwardly projecting portions 14 and 15 imbedded in the concrete so as to prevent wear of the concrete at the angle of the riser in the tread. The tread of the step may be ribbed or guttered as at 16 (Fig. 5) if desired in the usual way.

I have illustrated a simple, inexpensive, easily constructed, rugged insert for the purpose described, but I wish it to be understood that I do not wish to be limited to the exact details of construction shown, because I am aware that the changes in form, proportion and minor details of construction may be resorted to without departing from the spirit of the invention or sacrificing any of its advantages.

In Fig. 6 I have shown a slightly modified form of longitudinal bar consisting of two side strips 17 and 18 with the lead strip 19 between them. The lead strip 19 is the same width or substantially so throughout and it is provided with straight edges while the side strips 17 and 18 correspond in shape to the strip shown in the preferred form.

Ordinarily I recommend the construction shown in Figs. 1 to 5, but the modified form shown in Fig. 6 may be employed if desired.

What I claim and desire to secure by Letters-Patent is:

1. A step and an insert therefor, the insert comprising parallel bars longitudinally of the step having upper edges flush with the step to provide friction grips at the upper surface of the step so as to prevent slipping, and diamond shaped members connecting the bars, the diamond shaped members defining the width of the step.

2. An insert for flat surfaces comprising parallel bars, the upper edges of which are formed with corrugations, the corrugated portions of adjacent spaced bars being offset, the upper edges of the bars being substantially flush with the top surface so as to serve as friction members to prevent slipping.

3. An insert for flat surfaces comprising parallel bars, the upper edges of which are formed with corrugations, the corrugated portions of adjacent spaced bars being offset, the upper edges of the bars being substantially flush with the top surface so as to serve as friction members to prevent slipping; and transverse tie-bars visible at the surface in which the insert is imbedded so that the width of the insert will be apparent.

In testimony whereof I affix my signature.
GEORGE W. BROOKS.
